(57) **CLAIM**

We claim the ornamental design for a submersible pump housing, as shown and described.

DESCRIPTION

FIG. 1 is a perspective view of a submersible pump housing showing our new design;

FIG. 2 is one side elevational view;

FIG. 3 is a side elevational view rotated 90° from the position shown in FIG. 2;

FIG. 4 is a side elevational view rotated 90° from the position shown in FIG. 3;

FIG. 5 is a side elevational view rotated 90° from the position shown in FIG. 4;

FIG. 6 is a top plan view; and,

FIG. 7 is a bottom plan view.

The broken lines in FIGS. 1-7 are for illustrative purposes only and form no part of the claimed design.

1 Claim, 6 Drawing Sheets

OTHER PUBLICATIONS

Specification leaflet including photos of a model MH 480 Mody submersible pump that it is believed was publicly disclosed, on sale

or in public use prior to the filing date (Oct. 1, 2010) of the subject application.
